UNITED STATES PATENT OFFICE.

JOHN A. BOOZEL AND JOHN C. MOONEY, OF EMLENTON, PENNSYLVANIA.

THILL-COUPING.

SPECIFICATION forming part of Letters Patent No. 365,782, dated July 5, 1887.

Application filed April 26, 1887. Serial No. 235,975. (No model.)

To all whom it may concern:

Be it known that we, JOHN A. BOOZEL and JOHN C. MOONEY, of Emlenton, in the county of Venango and State of Pennsylvania, have 5 invented an Improved Noiseless Thill-Coupling, of which the following is a specification.

Our invention is illustrated in the accompanying drawings, in which Figure 1 is a side view of the coupling. Fig. 2 is a plan view 10 of the same. Fig. 3 is a central vertical longitudinal section, and Fig. 4 is a view of the coupling end of the thill in detail.

A is the axle of a vehicle, to which is secured, by a yoke, B, a hollow box or housing, 15 C, open on its front side. In this housing there fits a sliding journal-box, D, in which the thill E is journaled.

The journal-box D has a space, a, between its rear end, b, and the curved end of the thill, 20 and when the journal-box is inserted within the housing this space a is immediately in line with two apertures, c c, in the top and bottom of the housing. A portion of the end b of the box, however, always obstructs the rear portion 25 of the apertures c c when the box is in position in the housing. The journal-box is retained in position in the housing by a wedge-shaped coupling-pin, F, which is inserted in the apertures c c and through the space a. The 30 pin thus couples the thill to the axle and prevents the box being removed from the housing.

A set-screw, d, taking against one of the sides of the coupling-pin, prevents its accidental removal. As far as described, however, the 35 device is merely a coupling device, and would not prevent the rattling of the thills in case any of the parts should wear loose. The construction for rendering the coupling noiseless is an important feature of our invention. To 40 this end the housing C is formed on each side with a curved projection, e, against which abut lateral projections or cheeks f f, having curved faces conformed thereto on the thill E. The curved faces on the thill are concentric 45 with the journals g of the thill, so as to permit the raising and lowering of the thills. When, now, the thills are to be attached to the axle, the journal-boxes are inserted into the housings until the cheeks f f come in contact

with the projections e e. The wedge-shaped 50 coupling-pin is then driven into position, and, acting upon the rear end, b, of the box, where it partly obstructs the apertures c c, it forces the cheeks into close contact with the projections. The contact should be close enough to 55 permit the thills to rise and fall easily, but still so close as to permit no longitudinal movement of the journal-box.

In case of wear on the journals of the thill or on the cheek-faces, which would permit 60 longitudinal movement of the thill or the box, the set-screw can be unloosened and the wedge be driven farther in, thus again tightening the coupling and preventing all rattling of the same. To remove the thills all that is neces- 65 sary is to remove the coupling-pin.

By this simple and inexpensive device we provide a perfectly efficient and noiseless coupling.

We claim as our invention—

1. The housing secured to a vehicle-axle, having curved projections at its front, in combination with a sliding journal-box fitting in said housing, a thill journaled in said box having curved projecting cheeks adapted to said 75 projections, and a wedge-shaped coupling-pin, substantially as set forth.

2. The housing C, secured to a vehicle-axle, having apertures c c and curved projections e e, the sliding journal-box D, fitting in said 80 housing and having end b, which partly obstructs said apertures c c, and a thill, E, journaled in said box so as to leave a space, a, between it and the end b, said thill having curved cheeks f f, co-operating with said projections 85 e e, in combination with a wedge-shaped coupling-pin, F, inserted in said apertures c c and through said space a, and a set-screw, d, substantially as set forth.

In witness whereof we have hereunto signed 90 our names in the presence of two subscribing witnesses.

JOHN A. BOOZEL.
JOHN C. MOONEY.
